PORTABLE CAR STOP

Samuel L. Smith and James H. Smith, Hi Hat, Ky.

Application October 6, 1950; Serial No. 188,752

1. Claim. (Cl. 104—257).

1

This invention relates to portable car stops and more particularly to a portable stop which can be detachably secured to track rails at selected positions therealong and can be manually set to stop cars, such as mine cars, traveling on the track.

It is among the objects of the invention to provide an improved portable car stop of simplified construction and light weight which can be easily carried from place to place and quickly and easily connected to the track rails at desired locations, which is manually settable to its operative condition and manually releasable to permit cars to pass thereby, which cannot be accidentally displaced from its operative condition, which includes tie engaging means operative to restrain the car stop against being slid along a rail to which it is attached by impact of car wheels thereon, and which is simple and durable in construction, economical to manufacture, and positive and effective in operation.

Other objects and advantages will become apparent from a consideration of the following description and the appended claim in conjunction with the accompanying drawing wherein:

Figure 1 is a top plan view of a portable car stop assembly illustrative of the invention shown operatively connected to a track rail;

Figure 2 is a side elevational view of the car stop assembly illustrated in Figure 1;

Figure 3 is an end elevational view of the car stop assembly looking at the left-hand end of the stop assembly as viewed in Figures 1 and 2; and

Figure 4 is a fragmentary cross sectional view on the line 4—4 of Figure 3.

With continued reference to the drawing, the numeral 10 designates a track rail having a rail-head 11 supported on a web 12 carried by a flange 13 mounted on ties 14.

The portable car stop of the present invention includes a beam or bar 15 of I shaped cross section having a web 16 and flanges 17 and 18 extending one along each edge of the web 16 and each projecting symmetrically to opposite sides of the web. A rectangular plate 19 underlies the flange 18 and extends longitudinally therealong projecting beyond the adjacent end of the bar 15. This plate is secured to the flange 18 by suitable means, such as welding, and a second plate 20 is disposed on the plate 19 at the corresponding end of the bar 15 and is secured to the plate 19 by suitable means, such as welding. The plate 20 extends symmetrically

2

to the respectively opposite sides of the plate 19 substantially perpendicular to this latter plate and the ends of the plate 20 are bent in a direction away from the side of the plate 19 adjacent the bar 15 and are outwardly tapered to provide oppositely directed teeth 21 and 22 engageable with ties 14 between which the car stop is mounted or with the ground below the rail 10 to which the car stop is connected.

Abutment blocks 23 and 24 are secured to the plate 20 at the edge of the latter adjacent the bar 15 and at respectively opposite sides of the bar to engage the outer edge of the bottom flange of a rail to which the car stop is connected, as is particularly illustrated in Figures 1 and 2.

The plate 19 extends from the bar 15 beyond the side of the plate 20 remote from the adjacent end of the bar and carries on this extended end portion a spacer plate 25 and a button 26 rotatably secured to the plate 19 by a bolt or rivet 27. This button is provided at its opposite ends with different formations so that, when one end of the button is opposed to the abutment blocks it will firmly secure the car stop to a 20 pound rail and when the other end is opposed to the abutment blocks the button is effective to firmly secure the car stop to a 30 pound rail.

In connecting the portable car stop to a rail, the button is moved to a position at which it extends substantially transversely of the plate 19, the button and the extending portion of the plate 19 together with the plate 20 are then slid under the rail and the upper surface of the plate 19 between the teeth 21 and 22 is brought into engagement with the bottom surface of the rail flange 13 with the teeth 21 and 22 engaging adjacent ties or digging into the earth below the rail, and with the abutment blocks 23 and 24 engaging the outer edge of the rail flange 13. The button 26 is then turned until one upwardly turned end of the button rides over the inner edge of the rail flange, thereby clamping the bar 15 to the rail so that the bar extends outwardly from the rail substantially perpendicular thereto and in a substantially horizontal position.

A slide 28 is mounted on the upper flange 11 of the beam or bar 15 and has hooked or recurved end portions which engage under the flange 11 at the opposite edges thereof to hold the slide on the flange. A rectangular standard 29 extends upwardly from the edge of the slide 28 adjacent the button 26 and is provided near its upper end remote from the beam flange

17 with spaced apart apertures receiving bolts 30.

A wheel engaging block 31 is placed against the side of the standard 29 remote from the slide 28 and is provided with elongated apertures which also receive the bolts 30 and provide for vertical adjustment of the block 31 relative to the standard 29.

The car block 31 has concavely curved ends, the curvature of which is substantially the same as the curvature of the tires of the car wheels 42, so that when the car wheels engage the block, the tires will contact a maximum area of the end surface of the block.

Where the stop is used for stopping vehicles, such as mine cars, the block 31 may be formed of a hard wood to reduce the weight of the portable stop and also reduce the impact shock of the wheels against the block and avoid damage to the wheels.

An apertured lug 32 extends upwardly from the slide 28 at the end of the slide remote from the standard 29 and a rod 33 extends longitudinally of the bar 15 and has a screw threaded end portion extending through the aperture in the lug 32. The rod is secured to the lug for rotation relative to the lug but against longitudinal movement relative thereto by suitable means, such as the nuts 34 threaded onto the screw threaded portion of the rod and disposed at respectively opposite sides of the lug 32.

Apertured guide blocks 35 and 36 are secured to the bar 15 at spaced apart locations therewith and project upwardly from the top flange 17. The rod 33 extends slidably and rotatably through these guide blocks which hold the rods in position substantially parallel to the flange 17 of the bar. At its end remote from the lug 32 the bar is bent at right angles to provide a perpendicularly extending lever 37 for manually rotating and sliding the rod relative to the bar 15. This lever 37 is covered by a grip 38 of electrically insulative material to protect a person using the car stop against accidental electric shocks from the rail 10.

Two stops 39 and 40 in the form of short lengths of round iron stock are secured to the flange 17 at spaced apart locations between the guide 36 remote from the rail connected end of the bar and the end of the bar 15 remote from the rail connected end thereof. These stops extend transversely of the flange 17 and are secured thereto by suitable means, such as welding.

When the lever 37 is permitted to drop, it will engage behind one or the other of the stops 39 or 40, depending upon the position of the rod, to hold the rod in position against accidental displacement.

After the bar 15 has been connected to the rail 10 in the manner indicated above, in order to set the car stop to its operative position the lever or handle 37 of the rod 33 is manually raised and the rod is then manually slid along the bar 15 toward the rail 10 until the block 31 rests upon the railhead 11, as is particularly illustrated in Figures 1 and 2. The handle is then released and falls down behind the stop 39 so that the block cannot be accidentally displaced from the rail.

When it is desired to release the car stop to its inoperative position so that cars can pass by it,

the rod handle 37 is raised until it is released from the stop 39 and the rod is then manually slid along the bar 15 in a direction away from the rail 10 until the block 31 is disposed at a location spaced from the outer side of the rail. The handle is then released and will fall behind the stop 40 to prevent accidental movement of the block 31 back toward the rail 10. When it is desired to move the car stop to a different location, it can be released from the rail 10 by turning the button 26 to its released position and then drawing the plate 19 and associated elements out from under the rail.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claim are, therefore, intended to be embraced therein.

What is claimed is:

25 A portable car stop comprising an elongated bar having a flange along at least one edge thereof, means secured to said bar near one end thereof for releasably connecting said bar to a track rail to extend substantially perpendicularly therefrom, a slide mounted on said bar and engaging said flange to restrain said slide against separation from said bar while permitting sliding movement of said slide longitudinally of said bar, a wheel engaging block carried by said slide and movable therewith between an operative position in which it rests on a rail to which said bar is connected and an inoperative position in which it is spaced from one side of such rail, guides mounted on said bar at spaced apart locations therewith, a rod extending slidably through said guides and connected at one end to said slide for manually moving said slide along said bar between the operative and inoperative positions of said block, and stops secured to said bar at spaced apart locations therewith and engaging said rod to releasably lock said slide in the operative or the inoperative position of said block, said means secured to said bar for releasably connecting said bar to a track rail comprising a first plate secured to said bar and projecting from one end thereof, a second plate extending across said first plate at said one end of said bar substantially perpendicular to said first plate, said second plate extending substantially symmetrically to opposite sides of said first plate and having its ends disposed at an angle and tapered to provide teeth for engaging rail supporting material, and a button rotatively secured to said first plate adjacent the side of said second plate remote from said bar.
